UNITED STATES PATENT OFFICE.

JAMES F. McELROY, OF ALBANY, NEW YORK; SUSIE HALE McELROY, EXECUTRIX OF
SAID JAMES F. McELROY, DECEASED, ASSIGNOR TO CONSOLIDATED CAR-HEATING
COMPANY, A CORPORATION OF WEST VIRGINIA.

STEAM-TRAP.

1,145,909.

Specification of Letters Patent. Patented July 13, 1915.

Application filed January 12, 1912. Serial No. 670,898.

To all whom it may concern:

Be it known that I, JAMES F. McELROY, a citizen of the United States, residing at Albany, county of Albany, State of New York, have invented certain new and useful Improvements in Steam-Traps, the following being a full, clear, and exact disclosure of the one form of my invention which I at present deem preferable.

10 For a detailed description of the present form of my invention, reference may be had to the following specification and to the accompanying drawings, which illustrate my invention.

15 Figure 1 is a vertical axial section through the trap on the line 1—1 of Fig. 3; Fig. 2 is a view thereof from the outside; Fig. 3 is a horizontal section thereof on the line 3—3 of Fig. 1, and Fig. 4 is a plan thereof.

20 My invention relates to steam traps, for car heating systems in particular, and is shown as applied to a so-called "vapor" system of heating wherein the inflow of steam to the radiator pipes is controlled by 25 the temperature of the outflow from said pipes.

In a prior application for patent, Serial No. 646,606, filed August 29, 1911, I have shown and described a steam trap wherein 30 the high-pressure chamber is separated from the low-pressure chamber by a flexible wall acted upon externally by a thermostat and spring, while within the high-pressure chamber is a valve controlled by the movement of 35 said flexible wall.

40 In my present invention I also employ a flexible wall, but locate the same in a chamber on the outflow side of the said valve and subject to the pressure of the steam as it is admitted to the radiator pipes, such pressure 45 being higher than that of the outlet chamber, but not so high as that of the train-pipe. I also provide a casing having several sections, one of which serves as a trunk section and carries the ports and nipples for all of 50 the several pipes which connect with the trap. I have also devised a number of important features of construction which will be hereinafter described.

55 Referring to the drawings, the external casing of the trap is shown as divided horizontally at the three points, *a*, *b*, *c*, thereby forming four casing-sections *A*, *B*, *C* and *D*.

Section *B* is the trunk section containing all the entrance and exit ports which communicate with the apparatus. These are the train-line port *X*, the radiator admission-port *Y* and the radiator return-port *Z*. The section *A* consists of the cap-portion at the top of the trap which is secured to section *B* by bolts *a*¹, *a*², *a*³. The section *C* constitutes the vertical tubular portion of the casing being secured to section *B* by bolts *b*¹, *b*² and expanded at its lower end to receive section *D* which constitutes the "basket" for the controlling thermostat. This basket section has perforated walls and is secured to section *C* by hinge-bolts *d*¹, *d*².

Referring to Fig. 1, *E* represents a tubular sleeve known as the "bonnet" which is screwed into the wall that separates the chamber *U* (formed between said section *A* and the upper portion of trunk section *B*) and the chamber *V* (formed by the lower portion of trunk section *B* and the sections *C* and *D*). The bonnet *E* projects down into the chamber *V* to a point below the dividing line *b* between sections *B* and *C* and is squared at its lower end to receive a wrench, so that by detaching section *C* from 80 *B*, the lower end of the bonnet will be exposed and also accessible for screwing it, together with the devices carried thereby, into or out of its seat in the aforesaid separating wall. Likewise in assembling the trap, the 85 bonnet, and the other devices associated with it, can be screwed into place in the trunk section *B*, and the sections *A* and *C* thereafter secured to said trunk section. Between the said wall and a flange *e* on the 90 bonnet is a packing ring *f* which insures a tight joint when the bonnet is screwed home to its seat.

The bonnet carries on its upper side a flexible wall composed of a corrugated cylinder *F* which is seated on the upper surface of the bonnet and brazed or soldered thereto and which surrounds a tubular extension *e*¹ of the bonnet *E*. A rod *G* passes loosely through the bonnet so as to permit 100 of drainage of the cylinder *F* of any moisture therein, there being also small drainage ducts *e*² through the wall of the tubular extension *e*¹ which prevent accumulation of moisture between the outside of said extension and the inside surface of the flexible 105

cylinder. At the upper end of rod G is a disk G¹ which forms the upper closed end or head of the flexible cylinder. The rod G is also provided with guide-lugs g which move in vertical slots in the wall of extension e¹; these serve to prevent injury to the cylinder F by any attempt to turn the rod G on its longitudinal axis. An open-coil spring N surrounds the rod G below the bonnet and below the spring is guide-spider G² secured to the rod and serving as a guide therefor without preventing the flow of steam and water down upon the thermostat H. This thermostat is composed of a cylindrical shell of corrugated metal with a plate at top and bottom and is adapted to contain alcohol. On its lower end-plate is an internal guide-tube h in which plays a rod h¹ depending from the upper end-plate. By this means the two plates are maintained in parallel planes. On the outside of the upper end-plate is a hemispherical lug h² which seats in a cup-shaped socket on the underside of guide-spider G² and forms a ball-and-socket joint therewith. It will be observed that this joint lies in the line c which separates the covering-sections C and D and therefore it becomes possible to drop down the basket section D by removing one of the hinge-bolts d¹, d², and the thermostat will drop with it, separating from the rod G at the ball-and-socket joint. The thermostat can then be removed, or conversely can be applied, by seating it in the basket-section when the latter is dropped down, and then lifting the section into place with the lug h² in its position in the socket. In the chamber U is a lever T fulcrumed at t and one end of this lever consists of an inverted cup K which rests upon the disk G¹ forming the upper end of rod G, while the opposite end of the lever T carries the valve P which is adapted to close downward upon the valve-seat P¹. The purpose of the cup is to protect the flexible cylinder F from dirt and to overweigh lever T, causing the valve to stand open except when the thermostat H expands and forces the rod G upward. The valve P is jointed loosely to the end of lever T which bears on the valve through a central lug p thereon which allows the valve to be evenly seated, when closed, upon its valve-seat P¹. It should be observed that the steam pressure in chamber W, which is also the train-pipe pressure, will act against valve P to open it, in the event of its tending to stick to its seat.

The train pipe x enters a horizontal cylindrical extension S¹ of the trunk section B, which extension communicates with chamber W and contains a strainer S consisting of a thin-walled tube with numerous perforations, which is held in position by a screw plug S³ at one end of extension S¹.

having a blow-off port closed by a screw plug S². By this arrangement the strainer S can be readily removed for cleansing or the dirt can be blown out by opening the plug S².

In operation the steam from the train pipe x enters chamber W through the strainer S and then is admitted to chamber U by valve P as the thermostat H may permit. From chamber U the steam passes by port Y and radiator-pipe y to the radiator itself. After parting with most of its heat in the radiator, the steam, or the water produced by condensation of the steam, passes by the return radiator-pipe z to the chamber V of the trap and falls down on the thermostat H which is also exposed to the external temperature outside of the car by reason of the openings in the basket section D. So long as the resultant temperature of the thermostat is sufficiently high, the alcohol therein will expand and force the upper end plate together with rod G upward against the force of spring N and thereby close valve P upon its seat. When the resultant temperature of the thermostat is lowered sufficiently it will act reversely to allow the valve P to open by virtue of the steam pressure in chamber W and the overweighting effect of cup K. This will admit more steam to the radiator by the route described above, until the increased temperature of the radiator outflow thereby produced will cause the valve P to close again as heretofore described. The thermostat will in like manner respond to changes in temperature of the outside atmosphere.

What I claim as new and desire to secure by Letters Patent is:

1. In a steam apparatus, a casing containing two chambers, a flexible wall between the two chambers, a valve controlling admission of steam to one of said chambers, a support for said valve acting to normally unseat the latter, and a thermostatically controlled rod connected at one end with said flexible wall, same end of said rod also contacting with said valve support.

2. In a steam apparatus, a casing containing two chambers, a flexible wall between the two chambers, a valve independent of said flexible wall for controlling admission of steam to one of said chambers, means connected with said valve tending to normally unseat the latter, and thermostatic means including a rod connected with and inclosed by said flexible wall acting to expand and contract the latter, actuation of said valve unseating means being governed by movement of said flexible wall.

3. In a steam apparatus, a casing containing two chambers, a flexible wall between the two chambers, a valve independent

ent of said flexible wall for controlling admission of steam to one of said chambers, a rod engaging said flexible wall and inclosed by the latter to expand and contract said wall, said rod being independent of the valve, and means whereby actuation of said valve is governed by movement of said flexible wall.

4. In a steam apparatus, a casing containing two chambers, a flexible wall between the two chambers, a valve controlling admission of steam to one of said chambers, a support for said valve having an overweighted end acting to normally unseat the latter, and a thermostatically controlled rod connected at one end with said flexible wall, the same end of said rod also contacting with said valve support.

5. In a steam apparatus, a casing containing two chambers having an intermediate flexible wall, a valve in one of said chambers, an operating lever for said valve having one end resting upon said wall, means in the other chamber for expanding and contracting said flexible wall, and means whereby actuation of said valve operating lever is governed by movement of said flexible wall.

6. In a steam apparatus, a casing containing two chambers having an intermediate flexible wall projecting into one of said chambers, a valve in the last named chamber, a movable protecting wall inclosing said flexible wall and contacting therewith, said protecting wall being connected to said valve, and means in the other chamber for expanding and contracting said flexible wall, whereby actuation of said valve is governed by movement of said flexible wall.

7. In a steam apparatus, a casing containing two chambers having an intermediate flexible wall, a valve in one of said chambers, an operating lever for said valve provided with means for holding the latter normally unseated, means in the other chamber for expanding and contracting said flexible wall, said valve lever having a portion arranged to rest upon said flexible wall whereby actuation of the valve lever is governed by movement of said flexible wall.

8. In a steam apparatus, a casing containing two chambers having an intermediate flexible wall, a valve controlling admission of steam to one of said chambers, a supporting member for said valve provided with a protecting cup inclosing said flexible wall, and means for expanding and contracting said flexible wall.

60 9. In a steam apparatus, a casing containing two chambers having an intermediate tubular flexible wall projecting into the first chamber, the space within said projecting wall having a drainage connection with the second chamber, a valve controlling

admission of steam to the first chamber, and a thermostatically controlled operating device for said wall in the second chamber.

10. In a steam apparatus, a casing containing two chambers, a flexible wall between said chambers, a centrally pressed valve controlling admission of steam to one of said chambers, a valve operating lever provided with means tending to normally unseat the valve, an operating device for expanding and contracting said flexible wall, one end of said valve lever resting upon said flexible wall whereby movement of the valve is governed by movement of said flexible wall.

11. In a steam apparatus, a casing containing two chambers, a valve controlling admission of steam to one of said chambers, a bonnet between said chambers, a flexible wall supported by said bonnet, an operating rod for expanding and contracting said flexible wall, said rod being passed through said bonnet, said bonnet and rod being provided with complemental means for preventing relative rotation, and thermostatic means for actuating said rod.

12. In a steam apparatus, a casing containing two chambers with an intermediate tubular flexible wall projecting into the first chamber, a bonnet between the two chambers having a port extending into the space surrounded by said projecting flexible wall, an operating device for the wall passing through said bonnet, and a valve operated by said wall.

13. In a steam apparatus, a casing containing two chambers with an intermediate tubular flexible wall projecting into the first chamber, a valve controlling admission of steam to one of said chambers, a detachable bonnet between the two chambers having a portion extending into the said projecting flexible wall and provided with a duct for draining the space between said wall and the said bonnet, and an operating device for said wall passing from the second chamber through said bonnet.

14. In a steam apparatus, a casing formed in sections and containing two chambers with an intermediate flexible wall, a detachable bonnet carrying the flexible wall and projecting beyond the casing section in which said wall is mounted, a valve operated by said wall and an operating device for said wall connected therewith through the said bonnet.

15. In a steam trap, a casing formed in separable sections one being a basket-section for the thermostat, a thermostat detachably mounted in said basket-section, steam controlling devices extending through the other sections and operated by the thermostat, and a detachable connection between said thermostat and the devices operated thereby, said detachable connection being

approximately on the line of junction between said basket-section and the section adjacent thereto.

16. In a steam trap, the combination with 5 a casing, of a radiator control-valve, and an operating thermostat therefor comprising a flexible casing with top and bottom heads and a guide within the flexible casing for maintaining the heads of said flexible casing parallel during movement independently of said flexible wall.
17. In a steam trap, the combination with 10 a casing, of a radiator control-valve, and an operating thermostat therefor comprising 15 a tubular flexible wall with top and bottom heads and a guide within the flexible wall for maintaining the heads parallel during movement independently of said flexible wall.
18. In a steam trap, a casing comprising 20 superimposed separable sections containing three chambers: first, an admission-chamber containing a screen and adapted to communicate with the source of steam supply; second, a valve-chamber communicating 25 with the admission-chamber through the control-valve and with the radiator; third, a thermostat-chamber separated from the valve-chamber by a flexible wall, together 30 with operating connections from said wall to the valve in the valve-chamber and to the thermostat in the thermostat-chamber.
19. In a steam trap, a casing formed in 35 detachably connected superimposed sections one being a trunk-section containing the several inlet and exit ports and forming the body of the valve-chamber and another section secured to the trunk-section and forming the cover of the valve-chamber.
20. In a steam trap, a casing formed in 40 four detachably connected superimposed sections, one a trunk-section containing the several inlet and exit ports, one a cover-section for the valve chamber and secured 45 to the trunk-section, one a depending sec-

tion below the trunk-section and secured thereto, and the fourth a basket-section for the thermostat and secured to said dependent section.

21. In a steam trap, the combination with 50 a casing containing a valve-chamber and a thermostat-chamber beneath the valve chamber, the said chambers being separated by a perforated partition provided with a corrugated cylindrical wall, said partition 55 and wall being removable downwardly into the thermostat-chamber, of operating connections between said cylindrical wall and the valve on the one hand and the thermostat on the other hand.

22. In a steam trap the combination with 60 a casing containing a valve-chamber and a thermostat-chamber separated by a partition, said partition including a corrugated cylinder closed at one end and extending into the valve-chamber, operating connections between said valve and the cylinder, a thermostat in the thermostat-chamber and a vertical operating rod extending from 65 said thermostat up into said cylinder and guided therein for operating the valve through said cylinder, and a spring acting to press said rod downwardly.

23. In a steam trap, a separating device 75 between the valve and thermostat-chambers containing both a rigid portion for attachment to the casing and a flexible cylindrical portion closed at one end, an operating rod entering the said cylindrical portion, a 80 guide for said rod within said cylindrical portion, a thermostat for operating said rod, and a valve operated by the said rod.

In witness whereof I have hereunto set my hand, before two subscribing witnesses, this tenth day of January, 1912.

JAMES F. McELROY.
